CLAIM

The ornamental design for a patch for a glove, as shown and described.

DESCRIPTION

FIG. 1 is a front view of a patch while it is incorporated with base ball glove;

FIG. 2 is a prospective view thereof while in a flattened configuration;

FIG. 3 is a front view thereof while in a flattened configuration;

FIG. 4 is a top view thereof while in a flattened configuration;

FIG. 5 is a bottom view of thereof while in a flattened configuration;

FIG. 6 is a left side view of thereof while in a flattened configuration; and,

FIG. 7 is a right side view of thereof while in a flattened configuration.

The broken lines in FIG. 1 are for illustrative purposes only and form no part of the claimed design
